UNITED STATES PATENT OFFICE.

WILLIAM L. WEAVER, OF SWISSVALE, PENNSYLVANIA.

RAIL SEAT.

Application filed April 5, 1924. Serial No. 704,471.

To all whom it may concern:

Be it known that I, WILLIAM L. WEAVER, a citizen of the United States, residing at Swissvale, in the county of Allegheny and 5 State of Pennsylvania, have invented certain new and useful Improvements in Rail Seats, of which the following is a specification, reference being had to the accompanying drawings.

10 This invention relates to certain improvements in rail seats and has relation more particularly to a device of this general character constructed of concrete and it is an object of the invention to provide a device 15 of this kind with novel and improved means whereby a requisite cushion is afforded to the rail.

It is also an object of the invention to provide a novel and improved device of this 20 general character formed of concrete and wherein suitable rail holding or anchoring means is embedded within the concrete.

An additional object of the invention is 25 to provide a novel and improved device of this general character wherein a plurality of seats may be employed spaced one with respect to the other in a direction longitudinally of the rails and wherein adjacent seats are connected one with the other to maintain 30 the same in desired spaced relation.

The invention consists in the details of construction and in the combination and arrangement of the several parts of my improved rail seat whereby certain important 35 advantages are attained and the device rendered simpler, less expensive and otherwise more convenient and advantageous for use, as will be hereinafter more fully set forth.

The novel features of my invention will 40 hereinafter be definitely claimed.

In order that my invention may be the better understood, I will now proceed to describe the same with reference to the accompanying drawings, wherein:

45 Figure 1 is a fragmentary view in perspective illustrating a seat constructed in accordance with an embodiment of my invention and with a rail applied thereto;

50 Figure 2 is a view in top plan illustrating a plurality of seats constructed in accordance with an embodiment of my invention, the rail mounted thereon being shown in section taken horizontally through the web of the rail;

55 Figure 3 is a vertical sectional view taken

through my improved seat as herein disclosed, with certain of the parts in elevation and a second position of one of the anchoring or holding elements indicated by broken lines;

60 Figure 4 is a horizontal sectional view taken through the structure as illustrated in Figure 3 with portions in top plan;

65 Figure 5 is a view in perspective of one of the holding elements as herein disclosed, with the parts in separated relation;

Figure 6 is a view in perspective of a second holding member as herein disclosed.

70 As disclosed in the accompanying drawings, my improved seat comprises an outer housing or box 1 of requisite dimensions and formed of concrete, said housing or box 1 seating on and formed with a foundation 2 also of concrete and which foundation is preferably common to all of the housings or 75 boxes 1 associated with a rail of a trackway.

75 Snugly seating within the housing or box 1 is an expansible spring 3 of requisite tension and preferably spiral and which serves to constantly urge upwardly the sleeper or 80 pot 4 snugly fitting within the housing or box 1 from above and insertable through the upper open end of said housing or box.

85 The sleeper or pot 4 is also formed of concrete and is initially of a box type but after the fastening or anchoring elements have been properly positioned within said box like structure, a filler 5 of concrete is poured therein so that when said filler 5 hardens the anchoring or fastening elements 90 will be effectively maintained in applied or working position.

95 The fastening member A has engagement with the flange of the rail R at one side thereof and comprises an elongated member 6 of desired length and preferably angular in cross section, the upper portion of said member 6 being provided with a recess 7 to snugly receive the flange of the rail while the portion of the member 6 above or outwardly of the recess 7 is extended inwardly or laterally to provide an arm 8 to have close contact with the upper face of the associated flange of the rail and to contact with the web of the rail between said flange and the head or ball as clearly illustrated in Figure 100 3 of the accompanying drawings.

105 The second fastening or anchoring element B comprises an elongated member 9 of desired length and preferably angular 110

in cross section and which is provided in its upper end and in its outer face with an elongated recess 10 open at the top of the member 9. Snugly fitting within the recess 10 5 is a shank 11 carried by the outer end portion of the arm 12 adapted to overlie and contact with the second base flange of the rail R and to have close contact with the web of the rail between said flange and the head of the rail.

The outer or free end portion of the shank 11 is pivotally held within the lower end portion of the recess 10 by the pin 14 whereby the arm 12 may be swung toward or from 15 the rail R to facilitate the desired placing or removal of the rail. After the arm 12 has been properly engaged with the rail R, as illustrated in Figure 3, a pin 15 is inserted through the upper end portion of the 20 member 9 and an opening 16 provided in the shank 11 whereby the arm 12 is effectively locked in working position.

In order that the arm 12 may have 25 requisite swinging movement in the completed device to permit the desired application or removal of the rail, the upper surface of the rail R immediately adjacent the applied arm 12 and its shank is recessed or pocketed, as at 17.

30 In order to assure the requisite maintenance of the embedded end portions of the members 6 and 9, said members have common to the outer faces thereof the longitudinally spaced cross members 18. These members 18 are preferably arranged in parallelism and extend a desired distance beyond the opposite sides of the members 6 and 9.

As is clearly illustrated in the accompanying drawings, the member or spring 3 normally maintains the sleeper or pot 4 projected above the upper surface of the housing or box 1 so that said spring 3 will provide an effective cushion as the rolling stock 40 passes over the sleeper or pot 4.

45 In practice, the seats are arranged longitudinally of the rail of a track and in desired spaced relation and the foundation is first laid and is common to all of the 50 housings or boxes. These housings or boxes are preferably produced by mounting of the proper forms and after the walls of the 55 housings or boxes have suitably hardened the pot or sleeper 4 is then applied. I also find it of advantage to connect adjacent 60 housings or boxes in order to maintain the same in desired spaced relation and as herein disclosed such connection is provided by forming between adjacent housings or boxes 1 the longitudinally disposed and upstanding web 19 of concrete, said web being preferably integral with the foundation 2 and with the opposed walls of adjacent 65 housings or boxes 1.

In the road structure each rail of the 65 trackway embodies the arrangement of seats

as hereinbefore set forth with respect to only a single rail as this is believed to be sufficient for the purposes of disclosure.

From the foregoing description it is thought to be obvious that a rail seat constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. A rail seat comprising a housing open 25 at its top, a concrete pot fitting substantially snugly within the housing, an expandible member interposed between the applied pot and the bottom of the housing to normally urge said pot projected above the top of the housing, and fastening elements 30 embedded within the pot, said elements being positioned to engage a rail from opposite sides thereof.

2. A rail seat comprising a housing open 50 at its top, a concrete pot fitting substantially snugly within the housing, an expandible member interposed between the applied pot and the bottom of the housing to normally urge said pot projected above the top 100 of the housing, fastening elements embedded within the pot, said elements being positioned to engage a rail from opposite sides thereof, each of said elements comprising an elongated member, and cross members 105 secured thereto and extending beyond opposite sides thereof.

3. A rail seat comprising a housing open 110 at its top, a concrete pot fitting substantially snugly within the housing, an expandible member interposed between the applied pot and the bottom of the housing to normally urge said pot projected above the top 115 of the housing, fastening elements embedded within the pot, said elements being positioned to engage a rail from opposite sides thereof, each of said elements comprising an elongated member, and cross members secured to the outer faces thereof and extending beyond opposite sides thereof.

4. A rail seat comprising a housing open 120 at its top, a concrete pot fitting substantially snugly within the housing, an expandible member interposed between the applied pot and the bottom of the housing to normally urge said pot projected above the top 125 of the housing, fastening elements embedded within the pot, said elements being positioned to engage a rail from opposite sides thereof, each of said elements comprising an 130

elongated member, and a plurality of cross members being carried by each of the first named members and arranged in parallelism.

5. A rail seat comprising a housing open at its top, a concrete pot fitting substantially snugly within the housing, an expandible member interposed between the applied pot and the bottom of the housing to normally urge said pot projected above the top of the housing, fastening elements embedded within the pot, said elements being positioned to engage a rail from opposite sides thereof, one of the fastening members comprising an elongated member embedded within the pot, the upper end portion of the member being provided with a recess open at the top of the member, an arm provided with a shank extending within the recess, means for pivotally holding the inserted end portion of the shank to the member, said arm being movable toward or from a rail to permit the application or removal of said rail, and means coacting with the member and the shank for holding the arm in working position with respect to the rail.

6. A rail seat comprising a housing open

at its top, a concrete pot fitting substantially snugly within the housing, an expandible member interposed between the applied pot and the bottom of the housing to normally urge said pot projected above the top of the housing, fastening elements embedded within the pot, said elements being positioned to engage a rail from opposite sides thereof, one of the fastening members comprising an elongated member embedded within the pot, the upper end portion of the member being provided with a recess open at the top of the member, an arm provided with a shank extending within the recess, means for pivotally holding the inserted end portion of the shank to the member, said arm being movable toward or from a rail to permit the application or removal of said rail, and means coacting with the member and the shank for holding the arm in working position with respect to the rail, the upper portion of the pot adjacent to the arm and shank being recessed to permit requisite swinging movement of said arm and shank.

In testimony whereof I hereunto affix my signature.

WILLIAM L. WEAVER.
